(57) **CLAIM**

The ornamental design for a spinal fusion implant, substantially as shown and described.

DESCRIPTION

FIG. 1 is a perspective view of a spinal fusion implant showing our new design; FIG. 2 is a top view of the spinal fusion implant of FIG. 1; FIG. 3 is a first side view of the spinal fusion implant of FIG. 1; FIG. 4 is a first end view of the spinal fusion implant of FIG. 1; FIG. 5 is a second end view of the spinal fusion implant of FIG. 1; FIG. 6 is a perspective view of a spinal fusion implant showing an alternative embodiment of our new design; FIG. 7 is a first side view of the spinal fusion implant of FIG. 6; FIG. 8 is a first end view of the spinal fusion implant of FIG. 6; and, FIG. 9 is a second end view of the spinal fusion implant of FIG. 6.

The broken line showing is for the purpose of illustration and forms no part of the claimed design.

1 Claim, 5 Drawing Sheets

Related U.S. Application Data

continuation of application No. 12/396,458, filed on Mar. 2, 2009, now abandoned.
